UNITED STATES PATENT OFFICE.

GUSTAV BECHERER, OF BELLEVILLE, ILLINOIS.

LOCK.

1,411,401.

Specification of Letters Patent.

Patented Apr. 4, 1922.

Application filed April 16, 1919. Serial No. 290,479.

To all whom it may concern:

Be it known that I, GUSTAV BECHERER, a citizen of the United States, residing at Belleville, in the county of Saint Clair and State of Illinois, have invented certain new and useful Improvements in Locks, of which the following is a specification, reference being had to the accompanying drawings.

This invention relates to certain improvements in locks and has relation more particularly to a device of this general character especially designed and adapted for use in connection with automobiles or the like, and it is an object of the invention to provide a lock of this general character having novel and improved means whereby the steering post is held against rotation.

It is also an object of the invention to provide a lock of this general character including a shackle coacting with the post of the steering mechanism and which shackle when in one position holds the post against steering movement and when in a second position permits unobstructed operation of the post.

Another object of the invention is to provide a lock of this general character including a steering post engaging member together with permutation means coacting with said shackle for controlling the desired adjustments thereof, together with mechanism whereby the permutation means is held against removal or displacement when the shackle is in locking or holding engagement with the post.

The invention consists in the details of construction and in the combination and arrangement of the several parts of my improved lock whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a fragmentary view partly in top plan and partly in section illustrating a lock constructed in accordance with an embodiment of my invention and in applied position.

Figure 2 is an enlarged sectional view

taken substantially on the line 2—2 of Figure 1.

Figure 3 is a fragmentary view taken through the steering tube and post with the shackle shown in elevation and in a second position.

Figure 4 is a view partly in elevation and partly in section of the permutation mechanism as herein included.

Figure 5 is a view also partly in elevation and partly in section and particularly illustrating the means for holding the permutation means against displacement, and

Figure 6 is a transverse sectional view taken through the permutation means with certain of the parts in elevation.

As disclosed in the accompanying drawings, 1 denotes the steering gear tubing or column through which is directed the steering post 2. The portion of the post 2 adjacent the lower end of the tube or column 1 is provided with the opposed flattened faces 3 arranged substantially in parallelism and with which coacts the shackle S.

The shackle S has one end portion 4 enlarged and adapted to loosely surround the post 2 when the shackle is at the limit of its movement in one direction so that no hindrance or obstruction will be offered to the requisite rotation of the post 2 when it is desired to effect a steering operation. The opposite end portion 5 of the shackle is restricted transversely and includes the parallel members a which overlie the flat faces 3 of the post 2 when the shackle is at the limit of its movement in the opposite direction so that said shackle serves to hold the post 2 against rotation. In practice, it is particularly desired that the shackle S, or more particularly the arms a thereof, coact with the flattened faces 3 of the post 2 after said post has been rotated to throw or swing the steering wheels to substantially a quarter turn.

The shackle S is arranged within the tubing or column 1 and is carried by an end portion of an elongated arm 6 which extends through an opening 7 in the lower portion of the tubing or column 1 and the outer end of said arm 6 is provided with means for controlling the desired movement thereof for the requisite adjustment of the shackle S and which means are herein disclosed as of a permutation character.

Suitably secured to the dash D is a cas-

ing 8 having its outer face open and in which snugly fits a supplemental casing 9. The inner face of the casing 9 constitutes a removable plate 10 so that access may be had within the casing 9 after the same has been removed from within the casing 8. The outer face of the casing 9 is provided with the integral closing plate 11 provided with a suitable opening 12.

10 Disposed through the opening 12 and extending within the casing 8 is a spindle 14 having arranged thereon a plurality of nested sleeves 15 and said sleeves 15 and spindle 14 are capable of independent rotation.

15 The portions of the spindle 14 and the nested sleeves 15 within the casing 8 have secured thereto the discs 16 of the same major diameters and the periphery of each of said discs is provided with a recess or notch 17 adapted to substantially transversely align on proper manipulation of the spindle 14 and the sleeves 15. The outer end portions of the spindle 14 and the sleeves 15 are provided with operating flanges or knobs 18 so that said spindle and sleeves may be independently rotated in accordance with the desired combination to relatively adjust the discs 16 to bring the notches 17 into desired registration or alignment.

30 The assembled casings 8 and 9 are provided with the registering openings 19 in a side wall through which the outer end portion of the arm 6 is directed. Pivottally engaged with the end portion of the arm 6 within the casing 9 is an end portion of an elongated tumbler or swinging arm 20 and said tumbler or arm 20 is provided with a transversely disposed depending flange or lip 21 of a length to engage the peripheries 40 of the various discs 16 and of a width to drop within the registering or alining recesses 17. When the lip or flange 21 is seated within the alined or registering recesses 17, it will be obvious that upon rotation of 45 one or more of the discs 16, the arm 6 will be moved into position to adjust the shackle S into locking or holding position or vice versa.

I also find it of importance to provide 50 means whereby the casing 9 is locked or held against removal or displacement from within the casing 8 and particularly when the shackle S is in locking or holding position, so that the possibility of tampering 55 with the device by an unauthorized person is substantially entirely eliminated. As herein disclosed, the spindle 14 inwardly of the discs 16 has loosely mounted thereon a bushing or sleeve 22 provided with the oppositely directed arms 23 and pivotally engaged with each of said arms 23 is an end portion of a link 24 having its opposite end portion pivotally engaged with a bolt 25.

Each of said bolts 25 is slidably supported within an opening 26 in a side wall of

the casing 9 and which opening 26 registers with an opening or recess 27 in the adjacent side wall of the casing 8. One of the arms 23 has pivotally engaged therewith an end portion of another link 28 having its 70 opposite end portion pivotally engaged with the arm 6 so that when the arm 6 is moved in a direction to adjust the shackle S into locking or holding engagement with the post 2, the arms 23 will be swung in a direction 75 to move the bolts 25 outwardly and within the openings 27 so that the casing 9 is effectively held against displacement until after the arm 6 has been moved in the opposite direction to adjust the shackle S into the 80 inactive or neutral position illustrated in Figure 2 of the accompanying drawings.

When it is desired to move the arm 6 outwardly to cause the arms 6 of the shackle to coat with the flattened faces of the post 85 2, the discs 16 are rotated in a direction toward the tubing or column 1. At the beginning of this operation it is to be understood that the flange or lip 21 is seated within the aligned or registering recesses 17. As 90 the discs 16 are rotated and the arm 6 moved outwardly, the recesses 17, as the same pass downwardly beyond the vertical center, will free from the flange or lip 21 whereupon 95 said lip or flange will ride upon the unobstructed peripheries of the discs 16 and at a point in advance of the depending lug 20' carried by the upper portion of the supplemental casing 9. This depending lug 20' provides an abutment with which the free 100 end portion of the tumbler or arm 20 contacts to hold the arm 6 against movement inwardly of the casings 8 and 9.

When it is desired to retract the arm 6, the discs 16 are relatively rotated in accordance with a predetermined combination to cause the recesses 17 to align below the flange or lip 21 of the arm or tumbler 20 when the arm 6 is in extended position.

When the recesses 17 are so aligned, the 110 flange or lip 21 will fall therein so that upon requisite rotation of the discs 16, the arm 6 will be properly retracted.

When the arm 6 is retracted as disclosed in Figures 4 and 5 of the drawings, it is 115 not necessary that the flange or lip 21 be free of the recesses 17 and which disengagement is prevented by the depending lug 20'.

From the foregoing description, it is 120 thought to be obvious that a lock constructed in accordance with my invention is particularly well adapted for use by reason of the convenience and facility with which it may be assembled and operated, and it will 125 also be obvious that my invention is susceptible of some change and modification without departing from the principles and spirit thereof and for this reason I do not wish to be understood as limiting myself to the precise arrangement and formation of 130

the several parts herein shown in carrying out my invention in practice except as hereinafter claimed.

I claim:

- 5 1. A device of the class described comprising a casing, a second casing fitting therein and provided with registering openings, an arm extending through both of the casings and within the second casing, a
10 spindle rotatably supported by the second casing and extending within the same, a sleeve loosely mounted on the spindle and provided with oppositely directed arms, a bolt slidably supported within each of the
15 openings of the second named casing and adapted to be extended into the registering opening of the first named casing, a link operatively connecting each of said bolts and an arm of the sleeve whereby end-
20 wise movement is imparted to the bolt upon turning movement of the sleeve, a link operatively connecting one of the arms of the sleeve and the first named arm whereby movement of the first named arm imparts
25 rocking movement to the sleeve, and means for imparting movement to said first named arm.
2. A device of the class described comprising a casing, a second casing fitting
30 therein and provided with registering openings, an arm extending through both of the casings and within the second casing, a spindle rotatably supported by the second

casing and extending within the same, a sleeve loosely mounted on the spindle and 35 provided with oppositely directed arms, a bolt slidably supported within each of the openings of the second named casing and adapted to be extended into the registering opening of the first named casing, a link 40 operatively connecting each of said bolts and an arm of the sleeve whereby endwise movement is imparted to the bolt upon turning movement of the sleeve, a link operatively connecting one of the arms of the sleeve 45 and the first named arm whereby movement of the first named arm imparts rocking movement to the sleeve, disks rotatably mounted upon the spindle within the second named casing, said disks being provided 50 with peripheral recesses adapted to align, each of said disks being independently rotatable around the spindle, and an arm pivotally engaged with the portion of the first named arm within the second named 55 casing, said last named arm being provided with a lip of a length to engage the peripheries of the disks and of a width to drop within the recesses when in alignment.

In testimony whereof I hereunto affix my 60 signature in the presence of two witnesses.

GUSTAV BECHERER.
